(57) **CLAIM**

The ornamental design for an artificial Christmas tree, as shown and described.

DESCRIPTION

1. Artificial Christmas tree

1.1 is a front view of an artificial Christmas tree showing my new design;

1.2 is a back view thereof;

1.3 is a side view thereof;

1.4 is an opposite side view thereof;

1.5 is a top view thereof; and

1.6 is a perspective view thereof.

The present artificial Christmas tree design consists of a pedestal, a trunk, horizontal branches and a star on the top of the trunk; branches of different sizes are positioned through holes in the trunk successively from the shortest at the top to the longest at the bottom.
